UNITED STATES PATENT OFFICE.

LUTHER BENHAM, OF MARIANNA, ARKANSAS.

ACCOUNT-REGISTER OR COIN-COUNTER.

SPECIFICATION forming part of Letters Patent No. 357,361, dated February 8, 1887.

Application filed March 9, 1886. Serial No. 194,668. (No model.)

To all whom it may concern:

Be it known that I, LUTHER BENHAM, of Marianna, in the county of Lee and State of Arkansas, have invented a new and Improved 5 Account-Register, of which the following is a full, clear, and exact description.

The object of my invention is to provide an economical device adapted for use in the keeping of accounts between a store-keeper and his customer; and the invention consists of a case arranged to receive and hold two sets of checks, one set representing small amounts — as, say, from five to twenty-five cents—while the other set represents checks of from two dollars and a half to five dollars, the case being provided with an automatic indicating mechanism whereby the amount represented by the checks remaining in the case may be ascertained at a glance.

Reference is to be had to the accompanying drawings, forming a part of this specification, in which the same letters of reference indicate the same or corresponding parts in all the figures.

Figure 1 is a face view of my improved account-register. Fig. 2 is a vertical sectional view of the case, the checks, however, being shown in full lines. Fig. 3 is a cross-sectional view taken on line *xx* of Fig. 2. Fig. 4 is a 30 view of a modified construction. Fig. 5 is a view of another modified construction. Fig. 6 is a rear view of the construction illustrated in Fig. 5, the case being shown as opened; and Fig. 7 is a plan view of the same.

The case illustrated in the accompanying drawings consists, essentially, of a small cabinet, A, in which there are arranged two vertical compartments, B and C, each compartment being provided with an upper side opening that is closed by a door, D, formed with a catch, and arranged to be locked after the compartments have been filled with checks. In each of the compartments there is arranged a spiral spring, E, above which there is a block, F, carrying a pointer, *a*, which projects through a slot, *b*, formed in the inner wall of the compartment, and projecting inward behind a double graduated glass strip, G.

As best shown in Figs. 2 and 3, the compartments B and C are not of the same size, the idea being to provide against the mixing

of the checks for small and large amounts, the checks for large amounts being preferably slightly larger than those for small amounts.

Although any desired size of cabinet may be used, I prefer for general use a cabinet arranged to receive fifty dollars' worth of checks, said size being very convenient. The thickness of the checks H varies in accordance with the amount which they represent—as, for instance, the ten-cent checks are twice as thick as the five-cent checks, while the twenty-five-cent checks are five times as thick as the five-cent checks.

In the form of cabinet illustrated in Figs. 1 and 3, small checks to the amount of two dollars and a half are placed within the compartment C, the spring E, arranged in said compartment, being compressed, and fifty dollars' worth of two-and-a-half or five dollar checks are placed within the compartment B.

After the cabinet has been filled, the doors D are locked, a key being taken by both the merchant and the customer. As goods are bought, the checks representing the amount of the purchase-money are removed from the case, the doors D being first opened, and after small checks to the amount of two dollars and a half have been taken out of compartment C the small-check compartment is refilled and a check for two dollars and a half removed from the other compartment. As the checks are removed the pointers *a* are pressed upward, and will at all times indicate the exact amount represented by the checks contained within the two compartments—as, for instance, with the case in the condition represented in the drawings, the pointers indicate that three dollars have been removed from the case.

In Fig. 4 I represent a modified construction, wherein the inclosing-case is represented as provided with round-check-containing compartments, the said checks being held down against the tension of the springs, (not shown in this figure,) above which they are arranged, by a slide, I, arranged to be locked in place or moved from side to side, in order to permit the checks to be forced upward, as shown on the right of the figure under consideration, there being in this case a vertical slide, J, formed with a horizontal arm, K, beneath which the checks

are held, the slide J being arranged in ways formed at the side of the compartment; and it will be understood that after checks to the required amount have been removed the said slide is forced downward against the tension of the spring until beneath the level of the slide I, after which the said slide I is moved over the top of K and locked in place.

In the construction illustrated in the first 10 two figures of the drawings the checks are held down by blocks L, as clearly shown, the key-hole of the door-lock being shown at N.

In Figs. 5, 6, and 7 I illustrate a construction wherein the checks in the compartment 15 C do not in the aggregate exceed the sum of one dollar, while the checks in the opposite compartment, B, are all for a dollar or for multiples of a dollar, so that one of the pointers shown in Fig. 5, but not in Figs. 6 and 7 will 20 always denote the number of dollars while the other will denote the number of cents removed from the cabinet. In this case the cabinet is opened by a door, D, hinged at *p p* to the rear of the cabinet so as to open downward,

as indicated in Fig. 6. Below the door D of 25 the cabinet (shown in Fig. 6) there is a plate, R, that is embedded in the case and formed of any proper material, upon which orders, &c., may be written, and from which the orders may be readily erased.

Having thus fully described my invention, what I claim as new, and desire to secure by Letters Patent, is—

The account-cabinet herein shown and described, comprising the compartments B C, 35 spring-pressed follower-blocks F, having pointers projecting toward each other, a double graduated strip between said pointers and doors completely closing the upper ends of the compartments, and locking devices therefor, 40 whereby the contents of the compartments cannot be removed until the doors are opened, substantially as set forth.

LUTHER BENHAM.
